FOREIGN PATENT DOCUMENTS

DE 202006019735 U1 3/2007

Primary Examiner — Raphael Barkai*Assistant Examiner* — Randall Gholson(74) *Attorney, Agent, or Firm* — Harness, Dickey & Pierce, P.L.C.(57) **CLAIM**

The ornamental design for a wrench, as shown and described.

DESCRIPTION

FIG. 1 is a perspective view of a wrench according to the invention illustrating the top, rear and right sides of the wrench;

FIG. 2 is a perspective view of the wrench of FIG. 1;

FIG. 3 is a ride side elevation view of the wrench of FIG. 1;

FIG. 4 is a left side elevation view of the wrench of FIG. 1;

FIG. 5 is a top plan view of the wrench of FIG. 1;

FIG. 6 is a bottom plan view of the wrench of FIG. 1;

FIG. 7 is a front elevation view of the wrench of FIG. 1; and, FIG. 8 is a section view of the wrench taken along the line 8—8 of FIG. 7.

The broken lines shown on the drawings are included for the purpose of illustration only and form no part of the claimed design.
